UNITED STATES PATENT OFFICE.

WILLIAM MOLLER, OF NEW YORK, N. Y.

METALLURGIC FURNACE.

SPECIFICATION forming part of Letters Patent No. 249,971, dated November 22, 1881.

Application filed June 23, 1881. (No model.)

To all whom it may concern:

Be it known that I, WILLIAM MOLLER, a citizen of the United States, residing at New York, in the county and State of New York, 5 have invented new and useful Improvements in Metallurgic Furnaces, of which the following is a specification.

This invention consists in the combination, in a metallurgic furnace, of two pairs of retorts placed into the furnace-wall, a fire-place in one end of the furnace-wall, an arch above said fire-place, with openings in its sides and in its top, smoke-flues extending beneath the retorts, and communicating with the lateral openings 15 of the fire-arch and with the smoke-stack, smoke-flues extending on the sides and tops of the retorts, and communicating with the opening in the top of the fire-arch and with the smoke-stack, and a damper for opening or closing 20 the communication between the opening in the top of the fire-arch and the lateral and top flues, whereby the operation of heating the retorts can be readily controlled; further, in the combination, in a metallurgic furnace, of 25 two pairs of retorts placed into the furnace-wall, a fire-place in one end of the furnace-wall, smoke-flues extending beneath, on the sides, and over the top of the retorts, and communicating 30 with the smoke-stack, and air-flues formed in the furnace-wall and communicating at one end with the open atmosphere and at the opposite end, one with each of the retorts.

This invention is illustrated in the accompanying drawings, in which Figure 1 represents 35 a transverse vertical section in the plane $x x$, Fig. 3. Fig. 2 is a longitudinal vertical section in the plane $y y$, Fig. 1. Fig. 3 is a plan or top view, partly in section. Fig. 4 is a horizontal section in the plane $z z$, Fig. 1.

Similar letters indicate corresponding parts. In the drawings, the letter A designates the 40 furnace-wall, which surrounds the retorts B B' B² B³. Each of the retorts is provided with a mouth-piece, a, having doors b and an opening, c, so that by opening the doors the contents of the retort can be raked out through the opening c. The bottoms of the retorts B B' B² B³ are protected against the direct action 45 of the fire by tiles C, which rest upon transverse brick walls D.

E is the fire-place, which is built in the mid-

dle of the brick wall and near one of its ends, Figs. 1 and 4, and which is provided at its top with an arch, F, which is closed at both ends and extends from one end of the wall A to the other, and has openings d d in its sides and an opening, e, in its top. The transverse brick walls D extend up above the retorts, Fig. 2, and form the supports for the top of the furnace-wall, and they are provided with openings f in their outside lower corners, Fig. 1, so that the heated gases emanating from the fire can pass along the entire length of furnace-wall.

A longitudinal wall, G, which extends between the retorts B B' B² B³, Figs. 1 and 3, 65 forms an additional support for the top of the furnace-wall A. Near the front end of this longitudinal wall G is situated a damper, H, which serves to open and close an opening, g, in the middle of the tiles C, which corresponds 70 with the opening e in the top of the fire-arch, Fig. 1. This damper can be reached through a hand-hole, h, Fig. 2, in the furnace-wall, and if it occupies its closing position, as shown in Figs. 1 and 3, the heated gases emanating 75 from the fire escape through the lateral openings d d in the fire-arch and circulate all round the retorts before they can escape through the smoke-stack I. If the damper is opened, the largest portion of the heated gases passes 80 through the flues h, between the longitudinal wall and the retorts B B' B² B³, to the smoke-stack, thereby reducing the heating effect of the fire on the retorts.

In the lower portion of the furnace-wall A are 85 air-flues J J' J² J³, one for each retort. These air-flues communicate by channels j j' j² j³ with the open atmosphere, (see Fig. 4,) and by means of pipes k k' k² k³ with the mouth-pieces of the retorts, and as the air passes through these 90 air-channels it becomes heated, so that the same, on coming in contact with the heated ore in the retorts, promotes the combustion of sulphur, phosphorous, and other like impurities which are or may be mixed with the ore.

The air-flues may be arranged in a different manner from that shown in the drawings—for instance, they may be formed partly in the furnace-wall and partly in the sides of the retort—and I do not wish to confine myself to 95 the precise arrangement described.

On the top of the furnace-wall are placed a

series of pans, K K' K² K³, one over each of the retorts B B' B² B³.

5 In the bottom of each of the pans is an opening, *l*, which communicates by means of a channel, *m*, with an opening, *n*, in the top of the corresponding retorts, Fig. 2. Into each of the channels *m* is placed a flue, *M*, which is provided with a damper, *o*, and with an opening, *p*, in its side, which can be closed by a 10 gate, *q*.

The pans K K' K² K³ are filled with powdered ore, so that the same becomes heated before it is dumped into the retorts. When the gate *q* of one of the flues is opened the ore 15 from the corresponding pan can be dumped into the retort below. When the gates *q* are closed and the dampers *o* are opened the fumes from the retorts can escape through the flues *M*. By heating the ore in the pans K K' K² 20 K³ before introducing the same into the retorts a considerable saving in time and fuel is effected.

What I claim as new, and desire to secure by Letters Patent, is—

25 1. The combination, in a metallurgic furnace, of two pairs of retorts placed into the furnace-wall, a fire-place in one end of the furnace-wall, an arch above said fire-place, with openings in its sides and one opening in its top, smoke-flues 30 extending beneath the retorts, and communi-

cating with the lateral openings of the fire-arch and with the smoke-stack, smoke-flues extending on the sides and tops of the retorts, and communicating with the opening in the top of the fire-arch and with the smoke-stack, and a 35 damper for opening and closing the communication between the opening in the top of the fire-arch and the lateral and top flues, substantially as and for the purpose shown and described. 40

2. The combination, in a metallurgic furnace, of two pairs of retorts placed into the furnace-wall, a fire-place in one end of the furnace-wall, smoke-flues extending beneath, on the sides, and over the top of the retorts, and communicating with the smoke - stack, and air - flues formed in the furnace-wall and communicating at one end with the atmosphere and at the opposite end, one with each of the retorts, substantially as and for the purpose herein shown 45 and described. 50

In testimony whereof I have hereunto set my hand and seal in the presence of two subscribing witnesses.

WILLIAM MOLLER. [L. S.]
